UNITED STATES PATENT OFFICE.

LAURENCE S. LACHMAN, OF NEW YORK, N. Y., ASSIGNOR TO UNIVERSAL ELECTRIC WELDING COMPANY, OF NEW YORK, N. Y., A CORPORATION OF NEW YORK.

TRANSFORMER FOR ELECTRIC METAL-WORKING APPARATUS.

981,662.

Specification of Letters Patent. Patented Jan. 17, 1911.

Application filed February 9, 1909. Serial No. 477,002.

To all whom it may concern:

Be it known that I, LAURENCE S. LACHMAN, a citizen of the United States, and a resident of New York, in the county of New York and State of New York, have invented certain new and useful Improvements in Transformers for Electric Metal-Working Apparatus, of which the following is a specification.

10 My invention relates to improvements in transformers and more particularly to improvements in the secondary of that class of transformers used in electric metal working apparatus.

15 The main object of the invention is to avoid sliding contacts between the secondary of the transformer and the work-holders and to make the work-holders practically integral with the secondary and at the same 20 time permit them to be moved to and away from each other.

A further object is to avoid the necessity of flexible connections between the work-holders and the secondary and thus reduce 25 the number of parts and make the apparatus more efficient.

To these ends the invention consists in the improved form of transformer secondary hereinafter more particularly described and 30 then specified in the claims.

In the accompanying drawings, Figure 1 illustrates, in side elevation, the preferred form of secondary constructed in accordance with my invention. Fig. 2 illustrates an edge 35 view of the same. Fig. 3 is a plan view, the work-holders being removed. Fig. 4 is a side elevation of the secondary, showing the parts thereof as having been moved with relation to each other. Fig. 5 illustrates an 40 edge view of a modification.

The secondary is preferably formed of copper and is cast or otherwise suitably constructed. The secondary in the preferred form consists of two similar parts or structures, 1, 2, suitably formed in turns and provided with the usual gap 3 between the terminals thereof.

45 4, 5, indicate the primary coils located either side of the secondary, the core of the 50 usual construction and location not being shown.

One terminal of the part 2 of the secondary is preferably provided with a laterally projecting lug 6 while the opposite terminal

of the part 1 is provided with a similar lug 55 7 projecting in the opposite direction.

The two parts 1 and 2 are free to move longitudinally with relation to each other in the space between the primary coils 4 and 5, any amount of desired movement being obtainable and preferably electrical connection between the parts 1 and 2 being maintained.

The terminal blocks or work-holder bases, indicated at 8 and 9 are rigidly secured to 65 the secondary, one to each of the parts 1 and 2 thereof, by means of the lugs 6 and 7 and suitable fastening bolts 20 and may both be movable to and away from each other, owing to the capability of movement of the parts 70 of the secondary or one, such as 9, may be fixed and the other movable to and away from the fixed one 9. The work-holders or clamps secured to the bases 8 and 9 and the mechanism for moving them form no part of 75 this invention and are not shown.

The parts 1 and 2 preferably slide on each other and are held in close contact by any suitable means such as a bolt 10 secured to one part and working in a slot 11 in the 80 other part. If desired, a suitable insulating bushing 12 might be employed around the shank of the bolt 10 where it passes through and works in the slot 11 to prevent sparking when the apparatus is in operation. 85

My invention is not limited to any specific manner of mounting the work-holder bases or terminal blocks on the secondary as any suitable way of securing these parts might be employed without departing from the 90 spirit of the invention.

It will also be understood that the invention is not limited to any particular form of secondary nor to the arrangement of the parts with relation to each other as shown, a 95 modification being illustrated in Fig. 6 in which the two parts of the secondary do not slide in contact with each other, but are electrically united by means of flexible bars or cables 13, the main operation being the same 100 as in the preferred form.

What I claim as my invention is:

1. A transformer secondary consisting of two rigid turns in parallel planes and adapted to move longitudinally with relation to 105 each other.

2. A transformer secondary consisting of two rigid parts lying in parallel planes and

adapted to move longitudinally with relation to each other and each provided with a work-support on one terminal thereof.

3. A transformer secondary consisting of 5 two rigid turns lying in parallel planes and adapted to move with relation to each other in said planes to cause the terminals thereof to move to and away from one another.

4. A transformer secondary consisting of 10 two rigid turns lying in different planes and adapted to move with relation to each other to cause the terminals thereof to move to or away from one another and means for keeping said turns in electrical connection with 15 each other.

5. A transformer secondary consisting of two rigid structures adapted to slide longitudinally with relation to and in side contact with each other and carrying a work- 20 support at a terminal of each structure.

6. A transformer secondary consisting of two structures adapted to slide longitudinally with relation to and in side contact with each other and carrying a work-support at a terminal of each structure and 25 means adapted to keep said structures in close contact during said sliding.

7. A transformer secondary consisting of two structures lying in parallel planes and adapted to move longitudinally with relation to each other and each provided with a work-support on opposite terminals thereof. 30

Signed at New York, in the county of New York and State of New York this 5th day of February, A. D. 1909.

LAURENCE S. LACHMAN.
